UNITED STATES PATENT OFFICE.

MOODY L. CANOTT, OF WELLMAN, AND JOSEPH E. HALL, OF EAGLE GROVE, IOWA.

VAULT LATCH.

Application filed December 21, 1925. Serial No. 76,656.

This invention relates to vault latches and especially a lock whereby a vault door may be latched from the inside in a partially opened position.

5 In many instances where a daylight holdup or robbery takes place in a bank the employees are driven into the vault and are locked up by the robbers. Vaults of this character are practically air-tight and there is accordingly 10 considerable danger of suffocation unless the vault door is opened almost immediately after the robbery.

The object of the present invention is to provide an inside lock whereby the door is 15 automatically latched during a robbery in a partially opened position thereby insuring a sufficient supply of air if employees are locked within the vault, to provide a lock of this character which may be readily opened from 20 the inside whenever the employees deem it safe to escape and to provide a lock of this character which may be installed in practically any vault and which cannot be opened from the outside by the robbers once the door 25 has been closed.

One form of the invention is described in the following specification and illustrated in the accompanying drawings in which—

Fig. 1 is a detailed view of the latch showing it in retracted position.

Fig. 2 is a similar view showing the vault door closed and the latch in released position where it is ready to be projected when the door is opened.

35 Fig. 3 is a view showing the latch being projected while the door is being opened.

Fig. 4 shows the door locked in a partially opened position by means of the latch.

Fig. 5 is a plan section of the door and a 40 part of the vault showing the keeper engaged by the latch.

Fig. 6 is a transverse vertical section taken on line 6—6 Fig. 4.

Referring to the drawings in detail, particularly Fig. 5, A indicates the front panel of a vault and 2 the door whereby entrance is gained to the vault. Suitably secured on the inner face of the panel A as by bolts 3, is an angle bracket 4, secured on the face of the 45 angle bracket is a spacing plate 5 and slidably mounted thereon is a plate 6 on the outer end of which is formed a latch bolt 7. The plate is longitudinally slotted as at 8 and the slot is

extended at one end vertically as at 9 for purposes hereinafter to be described. Extending through the slotted plate is a bolt 10 and this bolt is provided with a head 11 to secure the latch plate against removal. Secured on the lower edge of the latch plate is a lug 12 and adapted to engage the same is a pawl 13. The pawl is pivotally mounted on the pin 14 and this pin also serves as a support or attaching means for one end of the helical spring 15 the opposite end of which is secured to a pin 16 carried by the latching plate 6. The function 65 of the spring is that of pulling the latch and plate into a forward position such as shown in Figs. 3 and 4, while the function of the pawl 13 is that of securing the latch and plate in a retracted position such as shown in Figs. 1 70 and 2.

The keeper indicated at 18 is nothing more or less than a rectangular shaped bar which is secured to the inner side of the door 2 by screws 19. This keeper is engaged by the 75 latch as shown in Fig. 4 when the latch assumes its forward position and it locks the door in a partially opened position as will hereinafter be described.

The door may assume two closed positions, 80 a partially opened position shown in Figs. 4 and 5 or a completely closed position as shown in Fig. 2. The partially opened position is locked by the latch and the keeper from the inside only and in the fully closed position it 85 is locked by means of the vault lock not here illustrated.

If it is desired to close the vault door and to lock it at night it is necessary to retract the latch bolt 7 as it would otherwise engage 90 the keeper and prevent complete closing and locking of the vault door. This is accomplished by merely grasping the latch plate and first pulling it upwardly out of the vertical extension of the slot 9 and then rearwardly along the longitudinal slot 8 until the lug 12 passes the pawl 13. The pawl is manually swung up to engagement with the lug and the latch is thus held in retracted position thereby permitting the vault door to be completely closed and locked. In the morning when opening the door it is essential that the latch should again be projected as it would otherwise be useless. The manually projecting mechanism would be of 100 105 comparatively little value as the employee

opening the vault door would be liable to forget and means are accordingly provided for automatically projecting the latch when the door is opened in the morning. To explain how this is accomplished it is perhaps best to state that the latch plate is covered and also partially guided by a housing or cover member consisting of a front plate 20 and a pair of end sections 21 and 22, this cover being held in position by means of a pair of screws or the like indicated at 23. Mounted on the door above the keeper is an angle-shaped plate 24. This plate engages the front end 21 of the lock cover when the door is closed and it pushes the lock cover together with the latch backwardly a sufficient distance to release the pawl 13 with relation to the lug 12. The pawl when released drops to the dotted line position shown at 13^a and as such is out of the way to permit automatic projection of the latch when the door is opened. In other words closing of the door at night pushes the latch plate back a sufficient distance to disengage it with relation to the pawl 13 and it is thus free to be projected by the spring 15 when the door is opened. As the door opens the latch plate is pulled forward by the spring until the vertical portion 9 of the slot is reached. The spring is disposed on an angle as shown in Figs. 1, 2 and 4 and it thus pulls the rear end of the latch plate downwardly as shown in Fig. 3. The forward end of the latch plate or the cover plate carried thereby is during this movement held up by the angle plate 24, but as the door continues to move open it is disengaged and the latch drops by gravity so as to assume the position shown in Fig. 4 and is thus in position to engage and lock the keeper if the door is closed by an unauthorized person during the day time.

From the foregoing it can be seen that a lock has been provided which will automatically lock a vault door in a partially opened position if closed by an unauthorized person, also that a lock has been provided which may be manually retracted so as to render it inoperative when it is desired to close the vault door and lock it, and further that means are provided for automatically projecting and rendering the latch operative when the vault door is open.

While certain features of the present invention have been more or less specifically illustrated we wish it understood that changes may be resorted to within the scope of the appended claims, similarly, that the materials and finish of the several parts employed may be such as the experience and judgment of the manufacturer may dictate or varying conditions may demand.

Having thus described our invention what we claim and desire to secure by Letters Patent is—

65 1. A device of the character described

comprising a support, a latch bolt slidably mounted thereon and adapted to assume a forward position and a retracted position, a door having a keeper mounted thereon adapted to be engaged by the latch bolt when in a forward position and the latch bolt adapted to lock the door and the keeper in a partially opened position, a guide for the latch bolt, a spring attached to the latch bolt and normally holding it in a forward position said latch bolt adapted to be manually retracted against the tension of the spring, a pawl engageable with the latch bolt to lock it in its retracted position and means actuated by the door for releasing the pawl and to permit the spring to automatically project the latch bolt.

2. In a device of the character described a support, a plate having a latch bolt formed on its forward end, said plate having an L-shaped slot formed therein, a pin secured to the support and projecting through the slot and permitting the plate and latch bolt to slide thereon and to assume a forward position and two retracted positions, a door having a keeper mounted thereon adapted to be engaged by the latch bolt when in a forward position, said latch bolt adapted to lock the door and the keeper in a partially open position, manually operated means for retaining the latch bolt in one of its retracted positions, means on the door adapted to retain the latch bolt in the second retracted position, said means being only operable when the door is completely closed, a spring connected with the plate and the latch bolt and adapted to project the same to its forward projected position, said spring cooperating with the means on the door to automatically project the latch bolt and the plate to its foremost position when the door is opened from a completely closed position.

3. The combination with a vault having a door of a keeper secured on the inside of the door, a plate reciprocally mounted and supported within the vault, said plate having a latch bolt on its forward end engageable with the keeper on the door, a housing carried by the latch plate and movable in unison therewith, a member on the door engageable with the housing and adapted to maintain the latch bolt in a partially retracted position when the door is completely closed, said latch plate having an L-shaped slot formed therein, a pin supporting the plate and projecting through the L-shaped slot, a spring attached to the plate and adapted to normally project the plate, the latch bolt and the housing to a forward position where the latch bolt will engage the keeper on the door, a lug on the plate and a manually operated pawl cooperating therewith to secure the plate, the housing and the latch bolt in a retracted position.

4. In a structure of the class described, the combination of a door element and a frame

element with a keeper mounted on one of said elements and projecting therefrom, and a latch bolt mounted on the other of said elements for sliding and pivotal movement, 5 means tending to move the latch bolt to projected or forward position, means for supporting said latch bolt for such sliding and

pivotal movement, said last-named means and said latch bolt having parts adapted to cooperate when the latch bolt is in its protracted position to prevent its return to retracted position. 10
